(57) **CLAIM**

The ornamental design for a nail polish bottle, as shown and described.

DESCRIPTION

FIG. 1 is a top perspective view of a nail polish bottle, shown partially assembled.

FIG. 2 is a front side elevation view of the nail polish bottle of FIG. 1.

FIG. 3 is a rear side elevation view of the nail polish bottle of FIG. 1.

FIG. 4 is a left side elevation view of the nail polish bottle of FIG. 1.

FIG. 5 is a right side elevation view of the nail polish bottle of FIG. 1.

FIG. 6 is a top plan view of the nail polish bottle of FIG. 1; and,

FIG. 7 is a bottom plan view of the nail polish bottle of FIG. 1.

(Continued)

The evenly dotted broken lines in the drawings illustrate unclaimed features of the nail polish bottle and form no part of the claimed design.

1 Claim, 6 Drawing Sheets
